UNITED STATES PATENT OFFICE.

ALFRED L. SCRANTON, OF WESTERN SPRINGS, ILLINOIS.

DOOR-HANGER.

SPECIFICATION forming part of Letters Patent No. 417,345, dated December 17, 1889.

Application filed January 29, 1889. Serial No. 298,018. (No model.)

To all whom it may concern:

Be it known that I, ALFRED L. SCRANTON, a citizen of the United States, residing at Western Springs, Cook county, Illinois, have 5 invented a new and useful Improvement in Door-Hangers, of which the following is a specification.

The object of my invention is to make a simple economical door-hanger; and the invention consists in making a door hanger having the features and combinations hereinabove described and claimed.

In the accompanying drawings, Figure 1 is a side elevation of my improved door-hanger 15 with a portion of the bed-plate broken away to show the slide therein, and Fig. 2 is a sectional view taken in line 2 2 of Fig. 1.

A is the portion of the bed-plate in which the slide moves for adjusting the position of 20 the hanger; B, the slide, and C the adjusting-screw.

In constructing my improved door-hanger I prefer to make it out of malleable iron instead of cast-iron. By making it out of 25 malleable iron I am able to make it much lighter than when it is made out of cast-iron, and to change and alter the parts or their relative positions, so as to fit them together, by a "former," and without "grinding" or 30 "filing." At the same time it is much stronger, and thus capable of supporting much heavier weights than is possible when it is made out of cast-iron. When made out of cast-iron, as at present, the wheel-frame is 35 liable to become broken by too much weight, by concussion when the door is shut carelessly, by a sudden starting of the door in cold weather, and in various other ways; but by making it out of malleable iron this liability 40 to breakage is entirely removed. So that by making the hanger out of malleable iron I am able to save time, trouble, and expense in fitting the parts together, and at the same time to make a lighter hanger and one capable of 45 supporting a greater weight and much less liable to breakage than is possible when the hanger is made from cast-iron.

My improvement relates to the means for adjusting the hanger. Stated generally, these 50 means consist of an inclined slide working in an inclined hollow part of the bed-plate, and an adjusting-screw for changing the position of the slide and through it the position of the hanger.

55 I prefer to make the entire bed-plate of one

piece—that is, to have its projecting portions integral with its base. The upper or inclined part of the bed-plate is grooved or hollowed from end to end and slotted in its top. The lower or inclined part of the wheel-frame is 60 made in the form of a slide and is adapted to fit and move in the groove of the inclined portion of the bed-plate, its shank fitting and moving in the slot, and the upper portion of the bed-plate is provided with flanges which 65 fit around and over the slide and secure and hold it in place without the aid of screws or other devices. The slide is preferably hollowed and provided with screw-threads inside, and in such case an adjusting-screw fitting and 70 working in its screw-threaded portion may be used to move the slide back and forth to change the position of the hanger; but, as the adjusting-screw may be used in different positions or ways, I do not wish to be understood as limiting myself to a construction in 75 which it is placed and operated inside the slide.

Whenever it is desired to separate the parts—the wheel-frame from the bed-plate— 80 it is only necessary to detach the adjusting-screw by unscrewing it. Of course this makes the separation of the parts very easy whenever the hanger is to be put up or whenever for any reason it is desired to separate 85 them.

What I have said about making the hanger of malleable iron is simply intended to show advantages which may be obtained by my construction; but of course it will be understood that I do not intend to limit myself to a hanger made out of malleable iron, my improvements being equally applicable to hangers formed from other material.

90 I claim—

95 In a door-hanger, the combination of a bed-plate provided with an inclined hollow slotted portion integral therewith and having inwardly-turned flanges on its upper edge, a wheel-frame provided with an inclined slide 100 fitting and moving in the hollow portion of the bed-plate and held from vertical displacement by the flanges thereof, and an adjusting-screw for moving the slide back and forth, substantially as described.

ALFRED L. SCRANTON,
